BAG CLOSURE

Frank Ahlburg, Los Angeles, Calif.

Application March 20, 1950, Serial No. 150,789

2 Claims. (Cl. 150—11)

1

This invention relates generally to a bag closure such as is applied to bags of the draw-string type used in the marketing of various products, including particularly vegetables and fruits.

It is an object of the invention to provide a bag closure of the above character which is relatively simple in construction and operation and which is useful in both closing and opening operations.

It is another object of the invention to provide a bag closure of the above character which is adapted for use in conjunction with present day draw-string bags which are used in marketing operations, and which constitutes an improvement over the present common practice of tying a knot in the draw-string to hold the bag closed.

Further objects of the invention will appear from the following description in which the preferred embodiment has been set forth in detail in conjunction with the accompanying drawings in which:

Figure 1 is a side elevational view showing the upper open end of the bag with my closure applied to the same;

Figure 2 is a side elevational view of the same bag but after the tightening of the draw-string;

Figure 3 is an enlarged plan view showing my retaining device in conjunction with the draw-string, and after the string has been tightened;

Figure 4 is a plan view of my draw-string retaining device, with the draw-string extending through the tunnels of the device;

Figure 5 is a section of the device taken along the line 5—5 of Figure 4; and

Figure 6 is a section of the device taken along the line 6—6 of Figure 4.

In Figures 1 and 2, I have shown the upper end of the bag 10 which is made of cotton netting and similar to bags such as are now commonly used for the marketing of various fruit and vegetables. In the past it has been common to apply a draw-string to the open end of such bags and when the bag has been filled at the packing plant the draw-string is tightened and then tied. This tying operation requires considerable labor and, in addition, makes it difficult to open the top of the bag, if, for example, one wishes to remove damaged or spoiled fruit or if one wishes to remove fruit in the event the contents of the bag are overweight or to add fruit if the contents of the bag are underweight.

A draw-string or cord 11 is applied to the bag near the upper open end thereof in the same manner as draw-strings have been applied in the

2

past. For example, if the bag material is say one-quarter inch mesh construction, the cord may be passed through every fourth or fifth mesh so that the cord can be readily drawn tight to hold the mouth of the bag closed. In a typical instance the cord is of the type made of twisted cotton fiber which is relatively soft in that it can readily be squeezed to a smaller diameter. For bags used in the marketing of oranges and potatoes, the cord may have a normal diameter of about three thirty-seconds of an inch.

Generally speaking cords of this type are usually impregnated with pigment or coloring material inasmuch as the pigment or coloring material is applied to the bag 10 and the cord 11 after the cord has been applied to the bag 10 as previously described, and after my retaining device 12 has been positioned generally as shown in Figures 3 and 4.

The construction of the retaining device 12 is illustrated particularly in Figures 3 to 6 inclusive. As illustrated, the device 12 is made of a strip 13 of suitable sheet steel metal, the end portions 14 of which are bent upon themselves to form generally a pair of cylindrical and parallel tunnels 16. One edge of the strip 13 forming the end of the tunnels 16 is belled generally as shown. The cord 11 extends through these tunnels 16 as illustrated in the drawings, and the inner diameter of the tunnels 16 is slightly smaller than the normal outside diameter of the cord 11 whereby the cord is squeezed somewhat as it passes through the tunnels 16 to provide a frictional retention while at the same time permitting the device 12 to be slid along the cord by applied manual force.

Figure 1 illustrates the position of the retaining device 12 before the bag is filled. The device 40 can be applied to the cord 11 at any time during or after the manufacture of the bag but, as previously indicated, it is usually applied before the coloring material or pigment is applied to the bag 10 and the cord 11.

Upon filling the bag with fruit or vegetables, the loop 17 is grasped by one hand of the operator and the device 12 grasped by the other hand. When the device 12 is slid to the position shown in Figures 2 and 3, the cord forms a loop which 50 gathers together the upper end of the bag to effectively close the same. In this manner the bag is retained in closed position. The bell 18 at the one end of the parallel tunnels 16 facilitates the sliding of the device 12 to the position 55 shown, in that the squeezing of the cord to the

smaller diameter to accommodate the same within the tunnel 16 is facilitated.

Upon release of the device 12, it generally attains the position illustrated in Figures 2 and 3 due to the friction between the device and the cord which is sufficient to prevent it from slipping along the cord to permit the bag to open. The inherent frictional engagement between the device 12 and the cord 11 due to squeezing the cord is supplemented by the effect of the engagement between the end wall 19 of the device and the portion of the cord immediately adjacent thereto which has not been squeezed. The non-sliding effect of the device 12 is further enhanced by the fact that when the device is in the position generally illustrated in Figures 2 and 3, the pull upon the same is almost at right angles to the longitudinal axis of the tunnel 16 rather than coaxial therewith.

Although the bag is held closed during handling, storage and shipment, if occasion should arise to open the bag as, for example, for the purpose of removing injured or spoiled articles of fruit or adding or removing some to attain the proper weight, this may readily be done by simply pulling outwardly upon the device 12 to return it to an open position.

This movement is resisted not only by the frictional engagement between the interior of the tunnels 16 and the cord 11 therewithin, which it will be recalled is considerably squeezed thereby, but also by the effect of the abrupt edge 19 of the tunnels 16 at that portion of the device remote from the belled edges 18. As has previously been pointed out the coloring pigment in the cord is primarily only upon the surface of the cord and as the sharp edge 19 of the device 12 is drawn along the cord, the pigment is scraped and caused to "pile up" so to speak, thereby tending to resist further unloosening sliding movements of the device 12.

It will be evident from the foregoing that I have provided a device which is extremely simple in construction and operation, which can be used to advantage in the fruit and vegetable packing industry.

I claim:

1. In a bag closure, a draw cord engaging the mouth of the bag, and a retaining device engag-

ing extended portions of the cord, said device comprising a single strip of sheet metal having opposite ends thereof bent upon themselves to form a pair of substantially cylindrical and parallel tunnels through which portions of the cord extend, the effective inner diameter of said tunnels being less than the normal outside diameter of the cord whereby said device frictionally retains the cord, the ends of said tunnels adjacent the bag being slightly belled to prevent undue abrasion of the cord, and the other ends of said tunnels having an abrupt edge to retard slippage of the device in a direction away from said bag.

- 15 2. In a bag closure, a draw cord engaging the mouth of the bag, and a retaining device frictionally engaging extended portions of the cord, said device comprising a single strip of sheet metal having opposite ends thereof bent upon themselves to form substantially cylindrical and parallel tunnels through which portions of the cord extend, the effective diameter of said tunnels being less than the normal diameter of the cord whereby said device frictionally retains the cord, sliding of said device along the extended portions of the cord in one direction serving to gather together the mouth of the bag to close the same, the ends of said tunnels adjacent the bag being slightly belled and the ends of the tunnel remote from the bag being abrupt to thereby retard slippage of the device along the extended portions of the cord in the other direction.

FRANK AHLBURG.
